CLAIM

The ornamental design for “novelty cap”, as shown and described.

DESCRIPTION

FIG. 1 is a perspective view of “novelty cap” showing my new design

FIG. 2 is a front elevational view of FIG. 1

FIG. 3 is a top plan view of FIG. 1

FIG. 4 is a right side elevational view of FIG. 1: the left side is a mirror image.

FIG. 5 is a bottom plan view of FIG. 1

FIG. 6 is a rear elevational view of FIG. 1

FIG. 7 is a perspective view of a second embodiment of “novelty cap” showing my new design

FIG. 8 is a front elevational view of FIG. 7

FIG. 9 is a top plan view of FIG. 7

FIG. 10 is a right side elevational view of FIG. 7: the left side is a mirror image.

FIG. 11 is a bottom plan view of FIG. 7; and,

FIG. 12 is a rear elevational view of FIG. 7.
